[57] CLAIM

The ornamental design for a pet tether, as shown and described.

DESCRIPTION

FIG. 1 is a front perspective view of the pet tether showing my new design;

FIG. 2 is a reduced top plan view thereof;

FIG. 3 is a reduced bottom plan view thereof;

FIG. 4 is a side elevational view thereof; and,

FIG. 5 is a cross sectional view taken along line 5—5 of FIG. 2.

The ground stake in FIGS. 4 and 5 is shown broken away for convenience of illustration and to show indeterminate length.

FIG. 1

FIG. 2

FIG. 3

FIG. 4

FIG. 5
